[57] **CLAIM**

The ornamental design for a combined stamp and cap therefor, as shown and described.

DESCRIPTION

FIG. 1 is a perspective view of a combined stamp and cap therefor showing my new design;

FIG. 2 is a rear elevational view;

FIG. 3 is a left side elevational view; the right side being a mirror image;

FIG. 4 is a top plan view;

FIG. 5 is a bottom plan view;

FIG. 6 is an exploded perspective view thereof;

FIG. 7 is a front elevational view of the stamp alone;

FIG. 8 is a rear elevational view thereof;

FIG. 9 is a left side elevational view thereof; the right side being a mirror image;

FIG. 10 is a top plan view thereof;

FIG. 11 is a bottom plan view thereof;

FIG. 12 is a top plan view of the cap alone; and

FIG. 13 is a cross sectional view taken on line 13—13 of the FIG. 4.
